UNITED STATES PATENT OFFICE.

JAMES NOBLE EDEN, OF SOUTH KENSINGTON, LONDON, ENGLAND.

MOTOR-CAR RADIATOR.

Application filed August 7, 1922. Serial No. 580,258.

To all whom it may concern:

Be it known that I, JAMES NOBLE EDEN, a subject of the King of Great Britain, residing at South Kensington, London, England, have invented certain new and useful Improvements in or Relating to Motor-Car Radiators, of which the following is a specification.

The object of this invention is to prevent the cooling water of an automobile engine from getting above a certain temperature and to prevent radiators from bursting, owing to the boiling of the water in case of a stoppage in the pipes due to solder or other foreign matter. The device comprises an attachment adapted to be secured to the radiator at the water filling hole in place of the ordinary radiator cap, and such attachment is provided with means, such as a cowl, similar to a ship's ventilator, having openings facing one to the front and the other to the rear of the car, and a partition arranged within the cowl so as to direct a stream of cold air into or near the surface of the water in the radiator and allow steam vapour to pass from the radiator through the rear portion of the cowl to the atmosphere. Gauze may be fitted across the front or rear cowl opening or both and at the bottom of the vertical pipes, which latter will usually be just clear of the water in the radiator. The rear wall of the intake portion of the cowl slopes forward and upwardly from the vertical pipe, hereinafter referred to, reaching nearly to the inlet end of the cowl and forming a partition to cause the current of air to flow from the forward end of the cowl down to the radiator water, and I provide a pipe leading from the rear portion of the cowl down to or into the radiator to cause water condensed in the rear portion of the cowl to flow back into the radiator.

I provide a throttle or like means for controlling the current of air, which may be in the form of a valve common to an aperture in the partition of the pipe and to the two passageways formed in the pipe by said partition. The rear cowl opening may be of any suitable shape and I may provide any other means for preventing condensed moisture from dripping or blowing off the attachment.

My invention will be more clearly under-

stood from the following description aided by the annexed drawings which show a simple construction of my device, in which:

Figure 1 is a vertical section.

Figure 2 is a side elevation.

According to the construction illustrated, I provide a tube A and on this tube A I mount a cowl B; and centrally within the tube I position partition C which has its upper end extending in an angular direction across the cowl B and its lower end extending preferably just below the lower end of the tube A, the tube and cowl being thereby divided into two compartments.

The cowl B is formed with a bell mouth D at its forward end and is contracted at its rear end as at E, said contracted portion having an opening at its center. The bell mouth and the opening at the rear end of the cowl are preferably covered with sheets of gauze F, G for the purpose of preventing insects getting into the cowl and tube.

The lower end of the tube A may be connected to the filling opening H of the radiator I in any desired manner, but in the construction shown I provide the exterior of the lower end of the tube A with screw threads and I also drill a hole in the radiator cap J and secure the tube A to the radiator cap J by two screw rings K, L which engage the screw threads of the tube A on opposite sides of the radiator cap J, and this forms an excellent means of securing my device to existing radiator caps.

I may form an aperture in the partition C and pivot to the tube a valve M which preferably is of "butterfly" form and fits the aperture in the wall C so as to leave two clear passages on either side of the wall C, and I connect to the spindle N of the valve, which is journaled in bearings formed in the tube A, a handle P positioned outside the tube A and working within a quadrant race Q so that, by operating the handle, the valve may be positioned to leave a clear passageway on both sides of the partition to and from the radiator or be actuated to completely shut off or throttle both passageways from the radiator.

I also form a second partition R in the cowl to the rear of the partition C to conduct the hot rising vapours to the upper portion of the cowl and so by the vapours coming in close proximity to the cold in-

flowing air ensure a better pull on the vapours by the movement of the vehicle, and from the rear portion of the cowl adjacent the partition R I conduct a pipe S down the 5 tube A and through the partition C, whereby all water of condensation will pass back into the radiator and, if desired, such pipe S may be provided with an extension S¹ to take the water of condensation directly into 10 the water of the radiator and so obviate any splashing.

By such a device the cold air flowing into the mouth D of the cowl and passing down the tube A into the radiator during the 15 travel of a vehicle to which it is affixed will act upon and cool the water in the radiator and the amount of the steam issuing from the opening at the portion E will indicate to the driver whether the water is being 20 kept cool enough.

What I do claim as my invention and desire to secure by Letters Patent is:—

1. A device of the character described comprising a pipe of which the lower end is adapted for connection to an automobile 25 radiator, a cowl connected to the upper end of said pipe and in communication therewith, said cowl having an inlet at its forward end and an outlet at its rear end, a 30 partition extending transversely of said cowl rearwardly and downwardly from the forward end of the cowl into said pipe and dividing said pipe into an inlet passage and an outlet passage, and a second partition extending partially transversely of the cowl 35 at a point rearwardly of the upper end of said pipe.

2. A device of the character described comprising a pipe having its lower end 40 adapted for connection with an automobile radiator, a substantially bell-shaped cowl connected to the upper end of said pipe

and in communication with the latter, said cowl having its mouth adapted to face forwardly of the vehicle to which the device is 45 attached and having an outlet at its rear end, a partition in said pipe dividing the pipe into an inlet passage and an outlet passage and extending upwardly beyond the upper end of the pipe transversely of said 50 cowl, a second partition in said cowl extending partially transversely of the latter rearwardly of said first-named partition, and a conduit extending through said pipe having its upper end connected to said cowl at a point rearwardly of said second partition and its lower end projecting beyond the lower end of said pipe. 55

3. A device for attachment to the radiator of a motor vehicle, comprising a pipe having a longitudinally extending partition therein forming a pair of passages, said partition having an aperture, a cowl connected to the upper end of said pipe and open to the atmosphere at both of its ends, said cowl having a partition forming a continuation of the partition in the pipe, and a valve in said pipe adapted to swing into position to close the aperture in said partition and also into position to close the 65 passages in the pipe.

4. A device for attachment to the radiator of a motor vehicle, comprising a cowl adapted to face forwardly on the vehicle and having forwardly and rearwardly directed apertures, a partition in said device forming passages communicating with the 75 radiator, said partition having an aperture, and a valve common to said aperture and to said passages. 80

In testimony whereof I have hereunto set my hand.

JAMES NOBLE EDEN.
